(57) **CLAIM**

The ornamental design for a tub for bathing, as shown and described.

DESCRIPTION

FIG. 1 is a right, top, front perspective view of a tub for bathing embodying our new design;

FIG. 2 is a top plan view thereof;

FIG. 3 is a front elevational view thereof, the rear elevational view thereof being a mirror image of the front shown;

FIG. 4 is a right side elevational view thereof, the left side elevational view thereof being a mirror image of the right side shown; and,

FIG. 5 is a bottom plan view thereof.

The broken line representations in the figures are for the purpose of illustration only, and form no part of the claimed design.

In a preferred embodiment, the nature of this product is as a plumbing fixture in the form of a bathing tub primary useful for washing the human body.
